UNITED STATES PATENT OFFICE.

ROBERT WHITEMAN, OF WEST FINLEY, PENNSYLVANIA.

LANTERN-RACK.

1,098,466.

Specification of Letters Patent.

Patented June 2, 1914.

Application filed May 14, 1913. Serial No. 767,689.

To all whom it may concern:

Be it known that I, ROBERT WHITEMAN, a citizen of the United States, residing at West Finley, in the county of Washington and State of Pennsylvania, have invented certain new and useful Improvements in Lantern-Racks, of which the following is a specification, reference being had to the accompanying drawings.

10 This invention relates to new and useful improvements in vehicle attachments, and more particularly to a lantern rack therefor, and my object is to provide a device of this character which is formed of a single strand 15 of material which may be quickly and readily applied to a vehicle or removed, when desired.

A further object of the invention resides in providing a rack which is designed to 20 provide spring clamping jaws for ready application to a portion of the vehicle body, and a still further object resides in providing portions on the rack which are adapted to receive, respectively, the base and head 25 portions of the lantern to securely retain the same in position.

A still further object of the invention resides in providing a device which is simple and durable in construction, inexpensive to 30 manufacture and one which will be very efficient and useful in operation.

With these and other objects in view, my invention consists in the novel features of construction, combination and arrangement 35 of parts which will be hereinafter referred to and more particularly pointed out in the specification and claims.

In the accompanying drawing forming part of this application, Figure 1 is a perspective view of the device showing the same applied to use. Fig. 2 is a side elevation thereof, showing a portion of the vehicle body in section. Fig. 3 is a rear elevation of the device, Fig. 4 is a plan view of the 45 same; and Fig. 5 is a detail perspective view showing clearly the formation of the upper portion of the rack.

Referring more particularly to the drawings in which similar reference characters 50 designate corresponding parts throughout the several views, 1 indicates a strand of wire which is looped intermediate of its ends to provide a pair of arms, and the loop is bent in a plane at right angles to the 55 general plane of the arms, as shown at 2.

The arms, at points adjacent the bent looped portion 2, are then bent upon themselves and disposed through the upwardly bent loop, and those portions of the arms which are bent to extend above the portion immediately continuing from the loop, are bulged somewhat outwardly, as shown at 3. These upper and lower sections of the arms which are disposed one above the other in spaced relation, form a base or the like 4, for the 60 rack to receive therein the base or lower portion of a lantern. In order that this base portion may clamp tightly around the base portion of the lantern and be sprung in position therearound, the lower sections of the 65 arms of this base converge forwardly, as is clearly shown in the drawing. The arms, after being disposed through the upwardly bent loop 2, continue upwardly, and at a point a short distance above said loop, are 70 again bent inwardly, as shown at 5. Continuing from this bent portion 5, the arms are again bent to extend upwardly to form the vertical portions 6. Continuing from the upper ends of the vertical portions 6, 75 the wire from both of the arms is coiled, as shown at 7, and then bent downwardly and again upwardly to form the clamping jaws or the like 8, which are disposed adjacent the vertical portions 6, but slightly spaced 80 therefrom to coöperate with the latter. The wire continuing from the clamping jaws or the like 8, after being again coiled in alignment with the coils 7, is bent forwardly over the base 4 to form the arms 9 and the extreme free ends of the latter are bent to 85 form hooks 10. These latter hooks are adapted to be engaged with the head portion of the lantern to lock the same in position 90 after the base portion thereof has been engaged with the base portion 4 of the rack.

In practice, the device is applied to the bed or body of a vehicle by engaging a portion of the latter between the arms 6 and the clamping jaws or arms 8, spring action 100 being capable between said portions 6 and 8 in view of the formation of the device of spring wire. The base portion 4 of the device is then somewhat spread so that the extreme base of the lantern may be disposed between the arms thereof, and the upper portions 3 of said base 4 will clamp tightly around the base of the lantern and hold the same in position. The hooks 10 on the arms 9 are then forced downwardly for spring 110

locking engagement with the under face of the head of the lantern, and said lantern under clamping action between the base and upper portions of the rack will be securely held in position in the latter.

From the foregoing, it will be seen that I have provided simple and inexpensive means for carrying out the objects of the invention, and while I have particularly described 10 the elements best adapted to perform the functions set forth, it is obvious that various changes in the form, proportion and in the minor details of construction may be resorted to without departing from the spirit 15 or sacrificing any of the principles of the invention.

Having thus described my invention, what I claim, is:

1. A lantern rack formed from a single 20 strand of wire looped and bent to provide a clamping base portion thereon, the wire continuing from said base portion being coiled and bent to provide spring clamping arms, said latter arms being disposed in a 25 plane to one side of the base portion and adapted for engagement with a stationary object, the wire continuing from said clamping arms being bent over said base portion to provide additional spring arms, and hooks 30 formed on the free ends of said spring arms

and adapted to coöperate with the base portion in retaining an object therebetween.

2. A lantern rack formed from a single strand of wire looped and bent to provide a pair of double spring arms designed to 35 form a base portion on the device, the upper sections of the double spring arms being bulged outwardly and disposed through the looped portion of the wire, the sections of the wire continuing from said upper sections being bent upwardly to form a body portion, the sections of the wire forming the body portion being offset intermediate of their ends, spring clamping members formed from continuations of the sections of the 40 wire forming said body portion and designed for coöperation with the latter to secure the device to an object, and additional spring clamping arms formed from continuations of the last mentioned clamping 45 arms, said additional spring clamping arms and the aforesaid base portion being adapted to retain an object therebetween.

In testimony whereof I hereunto affix my signature in the presence of two witnesses.

ROBERT WHITEMAN.
